No. 37,171.

Patented October 11, 1904.

UNITED STATES PATENT OFFICE.

FRANK SCHILLING, OF CINCINNATI, OHIO, ASSIGNOR TO THE CHARLES BOLDT GLASS COMPANY, OF CINCINNATI, OHIO, A CORPORATION OF OHIO.

DESIGN FOR A BOTTLE.

SPECIFICATION forming part of Design No. 37,171, dated October 11, 1904.

Application filed September 6, 1904. Serial No. 223,563. Term of patent 14 years.

To all whom it may concern:

Be it known that I, FRANK SCHILLING, a citizen of the United States, residing at Cincinnati, in the county of Hamilton and State of Ohio, have invented a new, original, and ornamental Design for Bottles, of which the following is a specification, reference being had to the accompanying drawings, forming a part thereof, in which—

tion. Fig. 3 is a side elevation. Fig. 4 is a section on the line 4-4, Fig. 1, and Fig. 5 is a perspective view.

What I claim as new, and desire to secure by Letters Patent, is—

The ornamental design for a bottle as shown.

FRANK SCHILLING.
